DOOR LATCH

Walter R. Schlage, San Francisco, Calif., assignor to Schlage Lock Company, San Francisco, Calif., a corporation of California

Application June 18, 1937, Serial No. 148,933

1 Claim. (Cl. 292—169)

This invention relates to door latches, and especially to improvements in the type of latch disclosed in my Patent No. 2,062,766, entitled "Door lock," issued December 1, 1936.

The object of the present invention is generally to improve and simplify the construction and operation of door latches, to provide a latch mechanism, and an improved housing therefor, in which the latch bolt is secured to a retractor plate which is actuated by one or another or both of a pair of telescoping spindles, and in which the retractor plate functions to dog or secure the spindles against endwise removal from the housing; to provide means actuated from the exterior of the door for releasing the spindles with relation to the retractor plate; and, further and more specifically stated, to mount a spring-actuated pawl on the retractor plate, which engages a stop on the housing so as to limit the movement of the retractor plate, thereby maintaining an interlock between the retractor plate and spindles, said latch being depressible by an implement inserted from the exterior of the door or housing to permit further movement of the retractor plate and thereby release of the interlock formed between the retractor plate and spindles.

The invention is shown by way of illustration in the accompanying drawings in which—

Fig. 1 is a horizontal central section taken through the stile of a hollow metal door, said section showing the latch housing, the latch bolt, the retractor plate and the spindles whereby the retractor plate is actuated;

Figs. 2 and 3 are perspective views of the telescoping ends of the spindles;

Fig. 4 is a longitudinal section showing the telescoping ends of the spindles;

Fig. 5 is a perspective view of the latch housing;

Fig. 6 is a perspective view of the retractor plate, the latch bolt secured thereto, and the depressible latch carried by the retractor plate;

Fig. 7 is a section in side elevation taken on the line VII—VII of Fig. 1, said section showing the retractor plate in interlocked position with relation to the spindles;

Fig. 8 is a section similar to Fig. 7, showing the retractor plate moved to a position where the spindles are released;

Fig. 9 is a perspective view showing the manner in which the latch housing and mechanism is installed in a rim lock; and

Fig. 10 is a sectional view of the spindles showing them interlocked to function as a single spindle.

Referring to the drawings in detail, and particularly to Figs. 1 to 6, inclusive, A and B indicate the opposite faces of the stile of a hollow metal door, and C the front edge thereof. Formed in the faces A and B are openings which

are provided for the reception of spindle bearings, as will hereinafter appear, and formed in the front edge C is an opening through which the lock housing, generally indicated at D in Fig. 5, is adapted to be inserted.

The housing shown in Fig. 5 is rectangular in shape, and consists of top and bottom plates 5 and 6 which are connected by front and rear end-plates 7 and 8. Extending through an opening formed in the front plate 7 of the housing is a latch bolt 9, and secured to the inner end thereof is a retractor plate generally indicated at E (see Fig. 6). The front end of the retractor plate is supported and guided by the latch bolt 9 which extends through the opening in the front plate 7, while the rear end is supported and guided by a pair of lugs 10—10 extending through slots or guideways 11—11 formed in the top and bottom plates 5 and 6 of the housing. On the rear end of the retractor plate is a cross-bar 12, and formed in front thereof is an opening 13 which is provided for the reception of the rollback portions 15 and 16 of a pair of telescoping spindles. These rollback portions are formed in the spindles by slotting them transversely, and the width of the slots thus formed is such as to permit the spindles to straddle the cross-bar 12 of the retractor plate. The spindles proper are indicated at 17 and 18, and each is provided with a permanently attached knob, said knobs being shown at 17a and 18a. Secured to opposite sides of the housing D (see Figs. 1 and 5) are plates 19—19, and formed in each plate is a central opening which is screw-threaded as shown at 20. These threaded openings serve the function of receiving and retaining spindle bearings such as shown at 21 and 22. The inner ends of the spindle bearings are threaded to screw into the openings 20 of the plates 19, and are in this manner secured. The spindle bearings 21 and 22 are of a diameter to receive the larger or exterior spindle 18. This spindle in turn forms a bearing for the spindle 17 which extends substantially through it.

On the forward end of the retractor plate E (see Figs. 6, 7 and 8) is pivotally mounted as at 24 a pawl 25, which is normally held in a raised or projected position by means of a spring 26. This pawl projects into a slot 27 formed in the upper plate 5 of the latch housing, and as such engages the rear end 27a of the slot, when the latch bolt 9 is fully retracted or depressed. This limited movement is the normal movement imparted to the retractor plate by means of the rollback portions 15 and 16 of the respective spindles, said movement being sufficient, as already stated, to cause complete retraction of the latch bolt, and thereby allow opening of the door. During normal movement, the cross-bar 12 of the retractor plate remains in the

transversely slotted portions of the respective spindles, and thus dogs or secures the spindles against endwise removal from the door or housing. On the other hand, if the retractor plate, 5 together with the cross-bar 12, is moved to the position shown in Fig. 8, the bar 12 will move out of the transverse slots of the respective spindles, and the spindles may then be freely removed in an endwise direction. This additional movement of the retractor plate and cross-bar is 10 imparted through a pin or rod 30 inserted through a pinhole opening 31 formed in the front plate 7 of the housing. When the pin is inserted it engages the inclined upper face of the pawl 26 and depresses the same. A further insertion of the pin or rod causes it to engage a shoulder 32 formed in the retractor plate, and continued insertion forces the retractor plate rearwardly until it finally assumes the position shown in 15 Fig. 8. Both spindles will then be fully released, and each may be removed. To re-insert the spindles the same operation will be necessary, and when they are inserted, and the transverse slots are brought into alignment with the bar 12, then the pin 30 may be removed, and the retractor will immediately be projected to assume the position shown in Fig. 7, due to the tension 20 of the springs 33 interposed between the bar 12 and the rear plate 8 of the housing.

30 To install a lock of this character, the lock housing is inserted between the opposite faces A and B of the stile through an opening formed in the edge or face C of the stile. The housing is held in this position until the two spindle bearings 21 and 22 are inserted and screwed into place, and when this is accomplished, the housing is fully secured, as it is supported at the rear end by the spindle bearings 21 and 22 and at the front end by the opening through which it is 35 inserted. Any suitable implement, such as the pin 30, is now inserted to depress the pawl 26, and to move the retractor plate to its rearmost position, or that shown in Fig. 8. The spindle 18 is then inserted, and thereafter the smaller or telescoping spindle 17. The spindles are turned by 40 means of their respective knobs until their transverse slots align with the cross-bar 12, and when this is done the pin 30 is retracted, and an interlock is immediately formed between the spindles and the retractor plate, which will be pushed 45 forwardly by the springs 33. During this forward movement the bar 12 enters the transverse slots of the respective spindles and the bolt 9 will at the same time assume a projected position as shown in Fig. 1. After installation, the 50 latch will operate in the ordinary manner; thus, rotation of either knob will cause rotation of the connected spindle, the rollback portions 15 and 16 will engage the front face of the bar 12, and as 55 the spindle or spindles are rotated, the bar, the retractor plate and the latch will move rearwardly, said rearward movement being limited by the pawl 26 when it engages the shoulder 27a, the movement being under all conditions sufficient to 60 permit complete retraction of the latch.

While the structure disclosed is particularly intended for a hollow metal door, it may obviously be employed in connection with wooden doors and the like, as a wooden door may be mortised 65 to receive the housing D; also it may be employed as a rim lock by inserting it in a housing such as shown in Fig. 9.

It is well known that door knobs are usually secured to spindles by screws and like means, and that they rattle loose and the knobs fall off from time to time. Such screws may be entirely eliminated in the structure here disclosed, as, 5 due to the fact that the spindles themselves are adapted to be removed from the housing, it permits permanent fastening of the knobs to the outer ends of the spindles by welding, soldering, 10 pinning, or other suitable means. By constructing the latch housing as shown in Fig. 5, it becomes possible to install it either in hollow metal doors, in rim locks or in wooden doors, and furthermore it is possible to secure the spindle bearings direct to the housing, due to the fact that 15 the plates 19 form a part of the housing, and the spindle bearings form a threaded connection therewith. By securing the housing within the door by means of the spindle bearings, all fastening screws are entirely eliminated, and removal or insertion of the lock is controlled entirely by a manipulation of an implement such as a pin or rod 30 (see Fig. 8).

While this and other features of the invention have been more or less specifically described, 25 I wish it understood that changes may be resorted to within the scope of the appended claims, and that the materials and finish of the several parts employed may be such as the judgment 30 or experience of the manufacturer may dictate.

When two telescoping spindles are employed as here illustrated, they may be independently operated or rotated, or the spindles may be interlocked as shown in Fig. 10 so as to rotate in unison as a single spindle, such interlocking between the spindles being accomplished by merely forming a notch 50 in the inner end of the outer spindle into which extends a lug 51 forming a part of the inner spindle. This type of interlock leaves the respective spindles free for endwise 40 removal when the interlock between them and the retractor is released, thus making it possible to employ permanently secured knobs whether the spindles function independently of each other or as a single rigid spindle.

I claim:

In a latch mechanism of the character described a housing comprising an outer end member and a pair of connected rearwardly extending arms, said end member and arms being constructed of flat material and forming a U-shaped housing, said arms being slotted adjacent their rear ends, and the outer end member having an opening formed therein, a latch bolt extending through the opening and guided therein, a retractor plate extending rearwardly between the arms, lugs on said plate extending into the slots formed in the arms, to guide and support the rear end of the retractor plate, said plate being secured at its forward end to the latch bolt and being supported and guided thereby; a pawl disposed adjacent the front end of the retractor plate, said pawl straddling the upper edge and extending longitudinally of the retractor plate, a pivotal connection between the forward end 65 of the pawl and the retractor plate, a spring between the opposite end of the pawl and the retractor plate, and a shoulder formed on one of the arms of the housing, with which the pawl normally engages to limit rearward movement of 70 the retractor plate.

WALTER R. SCHLAGE.
